UNITED STATES PATENT OFFICE.

ERNEST H. FOSTER, OF DONGAN HILLS, NEW YORK, ASSIGNOR TO POWER SPECIALTY COMPANY, OF NEW YORK, N. Y., A CORPORATION OF NEW YORK.

SUPERHEATER.

1,422,847.

Specification of Letters Patent. Patented July 18, 1922.

Application filed December 4, 1919. Serial No. 342,429.

To all whom it may concern:

Be it known that I, ERNEST H. FOSTER, a citizen of the United States of America, residing at Dongan Hills, Richmond County, 5 and State of New York, have invented certain new and useful Improvements in Superheaters, of which the following is a full, clear, and exact description.

The engineering problem of combining a 10 superheater with boilers of the Stirling type has been heretofore solved by placing such superheater, usually with vertically disposed tubes, in the second pass behind the front baffle. By this means the furnace gases after 15 passing over the first bank of tubes are deflected and sweep the superheater tubes.

This arrangement has proved to be the most practical and satisfactory, but it is not without certain objections which it has heretofore been very difficult to wholly overcome, 20 and this fact has led me to experiments and endeavors to devise some other equally if not better plan for the installation of superheaters in this type of boiler, which will 25 obviate the objections to the generally adopted plan. My present application is based upon the improved plan which I have succeeded in developing for this purpose.

In all boilers of this type, as is well known, 30 a series of substantially vertical banks of tubes connect a plurality of upper with one or more lower drums, and the upper drums are connected by circulating tubes. According to my present improvement I place a 35 superheater with horizontal rows of tubes between the first and second upper drums, and in the space between the upper and lower circulating tubes which connect them.

When thus located the effectiveness and 40 practicability of the superheater demand a special arrangement of the baffling, for which purpose I carry up the baffle wall immediately back of the first bank of boiler tubes to a point where it will deflect the gases 45 sufficiently to thoroughly wipe the superheater tubes, and a novel means of supporting the superheater, for which purpose I suspend it by rods from a beam carried by standards which are mounted on the first and 50 second boiler drums.

This is in general terms of description the improvement which forms the subject of this application. Other details of the construction and arrangement will be described by

reference to the accompanying drawings, in 55 which—

Fig. 1 is a sectional view of a Stirling boiler with a superheater located therein, in the manner above set forth.

Fig. 2 is a cross-section of the boiler on the 60 line 2—2 of Fig. 1.

The drawings show a specific form of boiler, which however is typical of a general class, in that it contains a plurality of upper drums 1, 2, 3, a lower or mud drum 4, and 65 banks of tubes 5, connecting the upper and lower drums.

Ordinarily and normally the baffling for such boilers comprises the baffles herein designated by the numeral 6, so that the gases 70 pass upward over the first bank and downward over the second. In these boilers also are circulating tubes 7 which connect the upper drums.

I place a superheater between the first and 75 second upper drums 1 and 2, and between the circulating tubes 7 which connect said drums. The superheater rests on a platform 8 which is suspended by rods 9 from a beam 10, which latter is secured to and carried by 80 standards 11, mounted on the two drums 1 and 2.

The superheater tubes 12 are arranged in horizontal rows and extend transversely across the space which they occupy. They 85 are connected to the usual headers 13 which are outside of this space, and the latter are connected with the boiler tubes and steam main in the usual manner.

In order that the superheater tubes may be 90 swept to the desired extent by the hot gases, a vertical slab of infusible material 14, constituting a baffle, is supported in any proper manner so that it will serve as an extension of the front baffle wall 6 and this slab is continued upward through the circulating tubes 7, and the superheater tubes 12, to a point 95 where it will insure the proper deflection of the gases to secure the desired degree of superheat. This may vary, and for that 100 reason the extent to which this vertical baffle is carried up through the superheater tubes may correspondingly vary, and in this way a variable degree of superheat may be obtained in a very simple and economical way.

Inasmuch as the hottest gases are deflected in this device so as to sweep the drums 1 and 2, it is desirable to protect these from the

excessive heat and for this purpose plates of infusible metal 15, such as cast iron, are supported over the exposed surfaces of said drums adjacent the superheater.

5. In all respects other than those herein noted, the construction of the boiler and superheater follows well known lines, and calls for no more specific description. This arrangement has proved to be eminently satisfactory and efficient. Access to the superheater for any purpose is rendered very easy, the construction of the boiler is interfered with to the least possible extent, and the matter of regulation and control made 10 easy and practical.

15. What I claim as my invention is:

1. The combination in a steam boiler of the Stirling type as herein described wherein in a plurality of upper drums are connected by circulating tubes, of a superheater with transverse parallel vertical rows of tubes placed between the circulating tubes connecting the first and second upper drums, a beam mounted on and above said drums, a support 20 for the superheater suspended therefrom and a vertical baffle which forces the furnace gases up and over the superheater tubes, said baffle extending up centrally between the transverse vertical rows of superheater tubes.

25. 2. The combination with a boiler of the Stirling type described, of a superheater having transverse horizontal rows of tubes in the space between the first and second upper drums and between the circulating tubes connecting said drums, of a vertical baffle which forces the furnace gases up and over the superheater tubes, said baffle extending up between the transverse horizontal superheater tubes.

30. 3. The combination in a steam boiler of the Stirling type as herein described wherein in a plurality of upper drums are connected

by circulating tubes, of a superheater placed in the space between the first and second upper drums and entirely above a group of 45 cross-circulator tubes, said superheater comprising a plurality of elements which extend laterally across the entire lower group of circulator tubes in a direction parallel to the drums and a baffle for directing the hot gases 50 from the boiler through the aforesaid group of circulator tubes and laterally across the superheater elements.

4. The combination in a steam boiler of the Sterling type as herein described wherein in a plurality of upper drums are connected by circulating tubes, of a superheater having the heating elements thereof placed in the space between the first and second upper drums and disposed entirely above the 60 lower circulator tubes, said elements extending parallel with the drums and being substantially coextensive in length with the depth of the boiler, and means for directing hot gases through the circulating tubes and 65 through the superheater.

5. The combination with a boiler of the Sterling type as herein described wherein a plurality of upper drums are connected by circulating tubes, of a main header leading 70 to the boiler and a main header leading to the steam main, said main headers being disposed laterally across the drums, of a plurality of depending headers extending downwardly from the said main headers and a 75 plurality of straight superheater elements disposed parallel to the drums and connecting the said last mentioned headers, said elements forming a superheater which is disposed entirely above the lower circulating 80 tubes and in the space between the drums.

In testimony whereof I hereunto affix my signature.

ERNEST H. FOSTER.
